UNITED STATES PATENT OFFICE.

IGNATZ WASSERSTROM, OF NEW YORK, N. Y.

BARREL-TAP.

SPECIFICATION forming part of Letters Patent No. 579,354, dated March 28, 1897.

Application filed January 22, 1897. Serial No. 620,194. (No model.)

To all whom it may concern:

Be it known that I, IGNATZ WASSERSTROM, of New York, in the county and State of New York, have invented a new and Improved Bar-
5 rel-Tap, of which the following is a full, clear, and exact description.

This invention relates to tapping devices for barrels containing liquids under high pressure, such as beer, ale, and other fer-
10mented or distilled liquors; and the object is to provide a tap that will withstand a very high pressure, and in which the pressure will have a tendency to force the valve tightly in its seat, thus preventing any possible leakage
15 when the valve is closed.

I will describe a barrel-tap embodying my invention and then point out the novel features in the appended claims.

Reference is to be had to the accompanying drawings, forming a part of this specification, in which similar characters of reference indicate corresponding parts in all the views.

Figure 1 is a longitudinal section of a tap embodying my invention. Fig. 2 is an in-
25 terior view looking toward the inner end of the valve. Fig. 3 is an interior view looking toward the outer end of the valve, and Fig. 4 is a longitudinal section showing the valve in its closing position.

30 The valve comprises a bushing, as here shown consisting of two sections 1 and 2, having a screw-thread engagement one with the other, but it is obvious that this bushing may be made in one piece without departing
35 from the spirit of my invention. The section 1 has an exterior screw-thread whereby it may be securely fastened in the bung-hole of a barrel.

40 Removably attached to the inner end of the bushing is a cap-piece 3, having a series of ports 4 for the discharge of liquid. The inner end of the section 2 of the bushing is pro-
45 vided with a beveled valve-seat 5, in which is mounted to rotate a correspondingly-shaped plug-valve 6. The smaller end of this tapered plug-valve, it will be seen, is toward the outer end of the bushing. Therefore the pressure of liquid on the outer end of said plug-valve will have a tendency to force the valve tightly
50 into its seat.

To prevent displacement of the plug-valve 6, I employ a screw 7, which engages in a

tapped hole in the cap 3 and impinges against the outer end of the plug-valve. At one side the valve 6 is provided with a port 8, which 55 extends from a communication with the interior of the cap 3 and is adapted for communication with a port 9, formed in the wall of the valve-seat and having communication with the interior of said bushing. The oppo-
60 site side of the valve 6 is provided with a port 10, extended from the interior of the bushing and adapted for connection with a port 11, formed in the wall of the valve-seat and having communication with the interior of the 65 cap 3.

It will be seen that the ports 8 and 10 ex-
65 tend, respectively, from opposite ends of the plug-valve and terminate intermediate of the ends of the valve, and that the ports 9 and 11 70 extend from opposite ends of the valve-seat and terminate intermediate of the ends there-
of. By turning the plug-valve to the position shown in Fig. 1 the liquid may flow out through the ports 8, 9, 11, and 10 and enter a tubular 75 key 12, having ports 13 through its wall with-
in the bushing.

From the inner end of the plug-valve 6 a lug 14 extends inward. This lug 14 is made an-
80 gular in cross-section, to be engaged by the correspondingly-shaped end of the tubular key 12. This key 12 has an enlarged portion
85 15, designed to engage in the outer end of the bushing, and it is provided with opposite wings 16, which may pass through opposite recesses 17, and when the key is turned may engage against the interior flange portions 18 of the bushing and thus secure the key in place.

Mounted on the tubular key 12 and bearing 90 against the inner end of the enlarged portion 15 is a washer 19, of yielding material—such, for instance, as rubber—and designed to engage against an annular flange 20 within the bushing. The outer end of the key 12 is pro-
95 vided with a screw-thread 21 to be engaged with a coupling for a pipe leading to a dis-
charge-faucet.

In operation, when the key is inserted and its inner end engaged with the lug 14, upon 100 turning the key the ports 8 and 9 will be put into communication and the ports 10 and 11 will also be put in communication. Upon turning the key in the opposite direction to

remove it from the bushing the ports will of course be turned out of alinement.

Having thus described my invention, I claim as new and desire to secure by Letters

5 Patent—

1. A barrel-tap, comprising a bushing designed to be engaged in the bung-hole of a barrel, a tapered valve-seat in the inner end of said bushing and having ports in its opposite sides extended respectively from opposite ends of said valve-seat to a point intermediate of its ends, a plug-valve mounted to rotate in said valve-seat and having ports in its opposite ends to points intermediate of the ends, a perforated cap on the inner end of the bushing, and a key for turning the valve, substantially as specified.
2. A barrel-tap, comprising a bushing having a tapered valve-seat in its inner end provided with opposite ports, the said ports be-

ing extended respectively from opposite ends of the valve-seat and terminating at points intermediate of the ends, a tapered plug-valve mounted to rotate in the valve-seat and provided with opposite ports respectively extended from opposite ends of the plug-valve to points intermediate of its ends, the smaller end of said plug-valve being toward the outer end of the bushing, a perforated cap-piece having screw-thread engagement with the inner end of the bushing, a screw engaging in a tapped hole in said cap-piece and impinging upon the plug-valve, a lug extended from the smaller end of the plug-valve, the said lug being angular in cross-section, and a tubular turning-key for engaging with said lug, substantially as specified.
